(57) **CLAIM**

The ornamental design for a hole punch for stationery, as shown and described.

DESCRIPTION

FIG. 1 is a front view of a hole punch for stationery showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a left side perspective view thereof; and,

FIG. 8 is a further left side perspective view thereof, showing the handle of the claimed design in an alternate position.

The features shown in broken lines in the drawings illustrate environmental matter and form no part of the claimed design.
